UNITED STATES PATENT OFFICE.

ALBERT G. PETIT, OF DETROIT, MICHIGAN.

STRAINER.

1,277,474.

Specification of Letters Patent. Patented Sept. 3, 1918.

Application filed July 5, 1918. Serial No. 243,361.

To all whom it may concern:

Be it known that I, ALBERT G. PETIT, a citizen of the Republic of France, residing at Detroit, in the county of Wayne and State 5 of Michigan, have invented certain new and useful Improvements in Strainers, of which the following is a specification, reference being had therein to the accompanying drawings.

10 This invention relates to a strainer for forcing fruits and vegetables that are in suspension, as in soups or the like, through a screen that eliminates large lumps or like matters. The invention includes an arrangement of parts whereby the device may 15 be readily cleaned and whereby it is easily adapted for various uses.

The invention consists in the matters hereinafter set forth and more particularly 20 pointed out in the appended claim.

In the drawings,

Figure 1 is a view, partially in section and partially in elevation, of a strainer that embodies features of the invention;

25 Fig. 2 is a view in plan thereof; and

Fig. 3 is a view in perspective, reduced, of the device.

Referring to the drawings, an annular spider 1 has a projecting arm 2 with depending lug 3 and a radially opposite handle 4 whereby it may be supported on the rim of a pail or cooking vessel. A conical sieve 5 of foraminous material depends from the spider, a bearing cap 6 being provided at the 30 lower end and stay members 7 aiding in supporting the latter directly to the spider and in stiffening the sieve 5.

A frame member 8, preferably in the form of a metal bar spans the spider 1 and has 40 downturned end portions or ears 9 through which clamping screws 10 extend to enter recesses in the spider and thereby locate the frame member.

A beveled pinion 11 is journaled in a boss 45 12 of the member 8, being retained therein against axial displacement by a washer 13

secured to the hub 14 of the pinion by screws 15 or other appropriate means. A hand shaft 16 operated by a crank 17 is journaled in a bearing member 18 mounted on the 50 frame 8, and is provided with a beveled gear 19 meshing with the pinion 11.

A helical presser 20 with screw blade 21 adapted to sweep the inner face of the screen 5 has a conical core 22 that is stepped in the 55 bearing 6, an upright spindle 27 from the core extending through the beveled pinion 11, and being either squared or splined for non-rotatable engagement therewith.

The proportions of the core 22 and blade 60 21 are such that the space between the screen and the core within the helix steadily diminishes so that solid articles caught by the revolution of the presser are gradually forced through the screen as they are worked down 65 toward the apex thereof.

Because of its construction the device is readily mounted on any cooking vessel or the like, is readily taken apart for cleaning and is extremely efficient in crushing and 70 straining solid or semi-solid matter.

Obviously, changes in the detail of construction may be made without departing from the spirit of my invention and I do not care to limit myself to any particular form 75 or arrangement of parts.

What I claim is:—

A strainer comprising a spider adapted to be supported on the rim of a cooking vessel, a bearing frame detachably secured across 80 the spider, a conical screen depending from the spider, a helical presser stepped at its lower end in the apex portion of the screen, a spindle extending from the presser through the bearing frame and means on the 85 latter for manually rotating the presser.

In testimony whereof I affix my signature in the presence of two witnesses.

ALBERT G. PETIT.
